UNITED STATES PATENT OFFICE.

JOHN M. JONES, OF PALMYRA, NEW YORK.

PAPER-CUTTING MACHINE.

SPECIFICATION forming part of Letters Patent No. 234,409, dated November 16, 1880.

Application filed July 14, 1880. (No model.)

To all whom it may concern:

Be it known that I, JOHN M. JONES, of Palmyra, in the county of Wayne and State of New York, have invented an Improvement in 5 Paper-Cutting Machines, of which the following is a specification, reference being had to the annexed drawings, in which—

Figure 1 is a side elevation of my improved paper-cutter. Fig. 2 is a plan view of the 10 same. Fig. 3 is an end view of the same. Fig. 4 is a detached view, showing the curved rack and spur-pinion.

My invention relates to paper-cutting machines; and it consists in the peculiar construction and arrangement of parts herein-after described, whereby the adjustment of the paper and operation of the machine by the workman without change of position are permitted, the operating-lever being for this 20 purpose located at or near one end of the machine and connected by gearing with the knife or blade, as hereinafter explained.

My improvement in operating the knife-bar of a paper-cutting machine is represented in 25 the accompanying drawings, in which A A is the frame of the machine; T, the table; S S, the standards; C, the cross-bar; B, the knife-bar; n, the knife; G G', the bevel-gears, and H the hand-lever.

My improved machine is constructed in the 30 manner customary with hand-power paper-cutters, and is provided with a suitable frame, A A, table T, suitable slotted standards S S arising therefrom and connected at their upper ends by the cross-bar C.

The knife-bar B is supported on diagonal links l l', pivoted to the cross-bar C, and has the usual diagonal cutting movement within slots in the standards S S. A spring, s, attached at its upper end to the cross-bar and at its lower end to the knife-bar, holds the knife-bar up when not in operation and counterbalances the weight of the lever H.

The knife-bar B is provided at one end with 45 a curved rack, R, having teeth on its lower curved side for engagement with the teeth of the spur-pinion P, as represented in Fig. 4. The rack is of a curved form suitable to keep

its teeth all the time in mesh with the teeth of the pinion P as the knife-bar descends with 50 a diagonal motion imparted to it by the pivoted links l l'.

The spur-pinion P is connected with the bevel-gear G', and they rotate on a shaft, e, Fig. 1, which is supported by means of suitable curved brackets d d', fastened to the standard S, or cast in one piece therewith.

The bevel-gear G, to which the hand-lever H is attached, is carried by a suitable stud fastened to the frame of the machine. The 60 gear G meshes with the gear G', and transmits the motion of the hand-lever to it, from which, by means of the pinion P and the rack R, the knife-bar and knife are operated.

The directions of the motions of the various 65 parts are indicated by the arrows in Figs. 1 and 3, and the positions of the knife-bar and hand-lever at the lower end of their motion are represented by the dotted lines R' and H', Figs. 1 and 3, respectively.

As the gears make but a part of a revolution, it is unnecessary to provide them with teeth on their entire circumference. The gear G' and pinion P may be attached to the shaft e, which is arranged to rotate in suitable bearings in the brackets d d' in this case.

My improved paper-cutter is provided with a paper-clamp operated by the hand-wheel D in the usual manner, and it may also have one or more paper-gages on the table.

The bevel-gear G is provided with a socket, f, into which the end of the hand-lever is inserted and held by a set-screw.

I am aware that it has been proposed to arrange the operating mechanism of a paper- 85 cutter at right angles to the knife-bar, and I make no claim thereto, broadly; but with the arrangement and construction of the parts shown and described I am enabled to greatly facilitate the operation of the cutter.

Having thus described my invention, what I claim is—

1. In a paper-cutting machine, the combination of the knife-bar suspended by links and provided with the rack R, the pinion P, meshing with said rack, hand-lever H, and bevel-

pinions G G', adapted and arranged to transmit power and motion from the lever to the pinion P, as set forth.

2. The herein-described paper-cutter, consisting of a table, a swinging knife-bar, provided with a curved rack, a pinion meshing with said rack, a hand-lever located at one end of the machine, and bevel-pinions connecting

the hand-lever and pinion, the whole arranged and operating as described, whereby the operator is enabled to adjust the paper and operate the knife without changing his position.

JOHN M. JONES.
